UNITED STATES PATENT OFFICE.

FREDERICK O. GAMBLE, OF CHICAGO, ILLINOIS.

DENTAL FLOSS-HOLDER.

1,102,401.

Specification of Letters Patent. Patented July 7, 1914.

Application filed December 28, 1912. Serial No. 738,972.

To all whom it may concern:

Be it known that I, FREDERICK O. GAMBLE, a citizen of the United States, residing at Chicago, in the county of Cook and State 5 of Illinois, have invented certain new and useful Improvements in Dental Floss-Holders, of which the following is a specification, reference being had to the accompanying drawings, forming a part thereof.

10 The purpose of this invention is to provide a convenient tool with which dental floss or any other thread may be held and manipulated for the customary purpose for which such dental floss is used, viz:—cleaning and removing obstructions from between the teeth.

It consists in the elements and features of construction shown and described as indicated in the claims.

20 In the drawings:—Figure 1 is a partly sectional side elevation of a tool embodying this invention, section being made through the stem of the handle axially with respect thereto. Fig. 2 is a partly sectional edge 25 elevation of the same, section being made through the portion of the handle at the line 2—2 on Fig. 1. Fig. 3 is a forward end view of the same. Fig. 4 is a dissected section of the bobbin-holder and bobbin, axial 30 with respect to the latter. Fig. 5 is a figure similar to Fig. 1, showing a modified form of the device. Fig. 6 is an edge elevation of the form shown in Fig. 5. Fig. 7 is a magnified detail section at the line 7—7 on 35 Fig. 5.

The device shown in the drawings comprises a fork between whose prongs, 1—1, the thread to be handled by the tool is to be stretched, and a handle for said form comprising a stem, 2, and a knob-like bobbin-holder, 3, at the end of the stem, remote from the fork. The device is shown in two forms. The form shown in Figs. 1, 2, 3 and 4 will be first described. In this form 45 the bobbin-holder, 3, and the fork are screwed into opposite ends of the handle stem, 2, the latter being tubular for providing an axial cavity through which the thread may extend from the bobbin to the 50 fork. The fork arms 1—1, are both curved side-ward at their extremities, as seen in Fig. 2, and are channeled upon the outer edge to accommodate the thread which is threaded through the axially apertured hub, 4, of the fork and out through the right-hand fork prong through an open eyelet,

1^a, provided at the base of that prong close alongside the hub, from which point it is drawn into the channel or groove, 1^b, on the outer side of said prong into which it extends into the self-threading eyelet, 1^c, at the end of the prong, thence across through the eyelet, 1^c, of the opposite prong from which it extends, lying in the groove, 1^b, of that prong to the base of the fork which has an open eyelet, 1^a, through which the thread is passed. It will be observed that an annular tablet or shoulder, 4^a, which is formed around the base of the threaded hub, 4, and the end of the tubular stem, 2, is flat, facing a corresponding annular tablet, 2^a, around the threaded counter-bore, 2^b, into which the threaded hub of the fork is screwed, and when the fork is threaded as described, it will be seen that the thread 70 extends twice across the annular tablet or shoulder, 4^a, so as to be bound or clamped between that shoulder and the opposed annular tablet or shoulder, 2^a, of the stem; and it will be observed also that the direction in which the portions, x^a, of the thread or floss, X, extend across said annular tablet when the fork is threaded as described, is such that when the fork is screwed into the stem so as to clamp the thread between the 80 two annular shoulders, the frictional drag upon the thread is in such direction at both of said portions, x^a, as to draw the thread from both the eyes, 1^c, so as to render it taut across the gap between them, and this 90 is the purpose of the threading arrangement described.

The knob-like bobbin-holder, 3, is divided axially with respect to its threaded hub, 3^a, the two parts being clearly seen in Fig. 4, 95 and each of them is provided at the center of the expanded portions, 3^b, which forms the bobbin casing, with a stud, 3^c, for centering the bobbin, 6, whose hub, 6^a, riveted to the lateral disk, 6^b, is axially bored at 6^c, 100 to receive said pins upon which the binder turns in unwinding the thread. The pins, 3^c, serve as rivets to hold both springs, 7, one in each member of the casing which bears upon the disks, 6^b, of the bobbin when 105 the casing members are brought together to engage and inclose the bobbin. It will be understood that said casing members are held together properly by having the threaded split hub, 3^a, screwed into the threaded 110 counter-bore at the outer end of the handle stem, 2.

It will be understood that the process of threading up the tool will be performed as follows: The knob handle and the fork being both unscrewed from the tubular stem, the 5 end of the thread will be passed axially through the stem. The bobbin will then be engaged between the two halves of the bobbin casing with the thread running out through the axial aperture formed through 10 the hub by the coincidence of the grooves, 3^a, in the facing surfaces of the hub halves, and the assembled members of the casing being then screwed into the handle, will be retained and will hold the bobbin snugly between them. The thread will now be threaded 15 through the axial aperture of the fork hub and out through the eyelet, 1^a, around through the eyelet, 1^c, of the fork and back through the aperture, 1^f, as described, all 20 this being done before the fork is screwed into the stem. This latter process being performed as soon as the shoulders, 4^a, and 25 2^a, begin to clamp the thread, the end of the latter which runs out through the eyelet, 1^f, may be drawn upon to take up the slack in the thread and then the screwing in of the fork being completed, the thread will be drawn taut and held.

In the form shown in Figs. 5 and 6, the 30 provision for holding the cord taut and for tightening it differs from the other form. For this purpose, there is provided a forked clamping device, 10, having a threaded stem, 10^a, which is screwed into the end of the tubular handle, 2, and by means of its fork arms, 10^b, pressing against the inner sides of the prongs of the fork, 1, this connection may be made to tightly clamp the said fork, 1, onto the end of the stem, 2. In this form, 35 the thread is threaded through the axial aperture, 10^c, of the stem, 10^a, and thence through an aperture, 10^e, of one of the fork arms, 10^b, from which it extends to and is threaded through an eyelet, 1^g, on the inner side of one of the fork arms. Thence it extends 40 through the self-threading eyelet, 1^c, at the end of the same prong and across through the similar terminal eyelet of the other prong and back through the eyelet, 1^g, of that prong, and thence out through an eyelet, 1^h, through the lower end of the last-mentioned prong. In the extent of the cord 45 from the eyelet, 10^e, to the eyelet, 1^g, and from the other eyelet, 1^g, to the eyelet, 1^h, the cord passes between gripping bosses, 1^k, on the prongs, 1 and 10^k, on the fork arms, 10^b, where it will be clamped and held by the same pressure of the fork arms, 10^b, by 50 which the fork, 10, will bind the fork 1, to the handle stem, 2 when the threaded connection at 10^a is tightened up. By making these two bosses, 1^k and 10^k, so that the one seats within the other, as indicated in Fig. 7, they have the effect of feathers or splines to 55 prevent the relative rotation of the two

forks, 1 and 10, when the handle stem is being screwed on, and so cause the clamping desired for both the purposes stated.

In both forms, all the eyelets may be self-threading; that is, constructed with lateral 70 entrance for the thread, as illustrated.

I claim:—

1. In a device for the purpose indicated, in combination with a fork having divergent prongs and means for holding a thread extended between the tips of its prongs; a handle member for the fork having a tubular stem and a clamp for connecting the fork to the stem, said clamp device being formed to enter between the prongs of the fork and bear against the inner sides thereof and having a threaded tang, the fork having an aperture through which the tang extends, and the tubular stem being threaded to receive the tang. 75

2. In a device for the purpose indicated, in combination with a fork having divergent prongs and means for holding a thread extended between the tips of its prongs; a handle member for the fork having a tubular stem and a clamp for connecting the fork to the stem, said clamp device being formed to enter between the prongs of the fork and bear against the inner sides thereof and having a threaded tang, the fork having an aperture through which the tang extends, and the tubular stem being threaded to receive the tang, the clamp having its tang axially apertured for the thread and having a thread guide eye through which the thread may extend from the axial aperture to the face of the clamp device which bears against one of the fork prongs, whereby the thread is clamped to the fork when the fork is clamped to the handle. 90

3. In a device for the purpose indicated, in combination with a fork having divergent prongs and means for holding a thread extended between the tips of its prongs; a handle member for the fork having a tubular stem and a clamp for connecting the fork to the stem, said clamp device being formed to enter between the prongs of the fork and bear against the inner sides thereof and having a threaded tang, the fork having an aperture through which the tang extends, and the tubular stem being threaded to receive the tang, the clamp being forked and the tang having an axial aperture leading into the fork gap, and one of the fork arms of the clamp having a thread eye leading to the side which bears against the inner side of the first mentioned fork. 110

4. In a device for the purpose indicated, in combination with a fork having divergent prongs and means for holding a thread extended between the tips of its prongs; a handle member for the fork having a tubular stem and a clamp for connecting the fork to the stem, said clamp device being 115 120 125 130

formed to enter between the arms of the fork and bear against the inner sides thereof and having a threaded tang, the fork having an aperture through which the tang extends, 5 and the tubular stem being threaded to receive the tang, the head of the clamp being forked and the tang having an axial aperture leading into the fork gap, and one of the fork arms of the clamp having a thread 10 eye leading to the side which bears against the inner side of the prong of the first mentioned fork, the opposite prong of said fork having a thread eye between the junction of the fork prongs and the bearing of the 15 clamp thereon.

5. In a device for the purpose indicated, a handle comprising a tubular stem and a bobbin holder having an axially-apertured and exteriorly-threaded hub adapted to be 20 screwed into one end of the tubular stem, said bobbin holder being divided axially with respect to said hub, each member thereof comprising, in addition to one-half the hub, one-half of a shell for inclosing a 25 bobbin, said halves having, respectively, studs projecting toward each other at their

centers for centering and retaining a bobbin in the shell.

6. In a device for the purpose indicated, a handle comprising a tubular stem and a 30 bobbin holder having an axially-apertured and exteriorly-threaded hub adapted to be screwed into one end of the tubular stem, said bobbin holder being divided axially with respect to said hub, each member 35 thereof comprising, in addition to one-half the hub, one-half of a shell for inclosing a bobbin, said halves having, respectively, studs projecting toward each other at their centers for centering and retaining a bobbin 40 in the shell, and springs mounted on said studs, adapted to yieldingly press upon the opposite sides of the bobbin when the shell-halves are bound together embracing the 45 bobbin.

In testimony whereof, I have hereunto set my hand at Chicago, Illinois, this 23rd day of December, 1912.

FREDERICK O. GAMBLE.
